FIGURINE

Dorothea Casady, West Los Angeles, Calif., assignor to Graham H. Harper, Santa Monica, Calif.

Application January 15, 1949, Serial No. 241

Term of patent 7 years

(Cl. D29—23)

To all whom it may concern:

Be it known that I, Dorothea Casady, a citizen of the United States, residing at West Los Angeles, in the county of Los Angeles and State of California, have invented a new, original, and ornamental Design for a Figurine, of which the following is a specification, reference being had to the accompanying drawing, forming part thereof.

In the drawing

Fig. 1 is a front elevational view of a figurine, showing my new design;

I claim:

The ornamental design for a figurine, as shown.
DOROTHEA CASADY.
